UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

OIL-WELL PACKER.

1,111,478.

Specification of Letters Patent. Patented Sept. 22, 1914.

Application filed March 7, 1914. Serial No. 823,175.

To all whom it may concern:

Be it known that I, PATRICK H. MACK, a citizen of the United States, residing at Bradford, in the county of McKean and 5 State of Pennsylvania, have invented certain new and useful Improvements in Oil-Well Packers; and I do hereby declare the following to be a full, clear, and exact description of the invention, such as will enable others skilled in the art to which it 10 appertains to make and use the same.

My invention relates to that class of devices commonly termed oil well packers used in connection with the casing and tubing of Artesian wells for shutting off water 15 from the lower levels of the well.

The invention in the present instance is directed more particularly to that class of packers which is to be applied on the tubing of deep wells adjacent to the oil bearing sand as in the case of oil wells, and while generally applicable to all deep wells which require packing is more especially 20 applicable to gas wells or flowing wells.

25 The object I have in view is the provision of a well packer which can be initially applied to the tubing low down, preferably a short distance above the bottom of the well, or at any desired point in the well, and one 30 which in case of spalling or crumbling of the walls of the well, will guard tubing against buckling or fracture and will be automatically re-applied or reset by the dropping of the tubing, and which also 35 can, after its first application, be progressively raised and reapplied at any point where the walls of the well will permit.

As now generally constructed all available well packers embody in combination 40 a packer body, a compressible and expandable packing of annular shape, an annular abutment, upon which the packing rests, means for transferring the weight of the tubing to the annular packing, and means 45 for supporting from the walls of the well the abutment on which the annular packing rests or is seated.

The means for supporting the abutment from or anchoring it to the walls of the 50 well may be broadly defined as of two kinds, first, such as can be manipulated to set and release the abutment without pulling the

string of tubing, and which does not require any contact with the bottom of the well, and, second, such as require contact with 55 the bottom of the well to set the anchoring devices or cause them to engage effectively the walls of the well.

With the first named means there is no provision to arrest, retard or cushion the 60 drop of the tubing in case of failure of the anchor to hold by reason of crumbling of the well walls, as frequently happens, and the unrestrained drop of the string of tubing, which may be thirty-five hundred feet 65 in length and weight seven tons, more or less, frequently results in buckling or fracturing the tubing with loss of time and labor if not loss of the well. For this reason it is generally deemed preferable to 70 employ as a packing for tubing in deep wells the last named means for actuating the anchor which supports the abutment, namely, one in which contact with the bottom of the well is required to set the anchor 75 or render it operative, and in which there is no material drop of the tubing in case the walls of the well spall or crumble, and this construction is preferred notwithstanding 80 that in case the anchor fails through spalling or crumbling of the walls of the well, there is no way of again applying the packing without pulling the string of tubing and increasing or diminishing the length of that 85 portion of the tubing which extends from below the packer to the bottom of the well, and, further, that there is no means of readily determining how much tubing must be added or removed to bring the anchoring 90 means into position where the walls of the well will hold.

To effect the purposes of my invention I combine with the body of the packer the usual or any approved annular compressible and expandible packing member, an 95 abutment therefor, means for anchoring the abutment on the walls of the well, said means adapted to be operated at will while the packer is suspended in the well, and a tubular extension member suspended from 100 and adapted to telescope with the body of the packer and actuate the anchor, whereby when the anchor is accidentally released by reason of the crumbling of the walls of the

well, or otherwise, the descent of the tubing is retarded, arrested and cushioned and the packing is automatically reapplied without injury to the tubing or packer, and a 5 wall packer involving such a combination of coacting elements embodies the main feature of my invention.

There are other, minor, features of invention involving particular combinations 10 as well as particular features of elemental construction, all as will hereinafter more fully appear.

In the drawings chosen for the purpose of illustrating my invention, the scope whereof 15 is pointed out in the claims, Figure 1 is a view in elevation, parts broken out, of a well packer embodying my invention. Fig. 2 is a longitudinal central section of the well packer shown in Fig. 1, showing the 20 relation of the coacting parts to each other and to the walls of the well before the packer is set or applied to the walls of the well. Fig. 3 is a sectional view similar to Fig. 2 showing the relations of the coacting 25 parts after the packer has been set or applied to the walls of the well. Fig. 4 is an enlarged detail sectional view showing the manner of controlling the anchoring devices when inserting the packer in the well. Fig. 30 5 is a transverse sectional view of the packer taken in the plane of the line 5—5, Fig. 1, and Fig. 6 is a transverse sectional view of the packer taken in the plane of the line 6—6, Fig. 1.

Like symbols refer to like parts wherever they occur.

I will now proceed to describe my invention more fully so that others skilled in the art to which it appertains may apply the 40 same.

In the drawings, 1 indicates a reducing coupling which forms the upper end of the packer proper, said coupling threaded internally as at 1^a for the reception of the 45 lower end of a string of tubing *a* with which the packer is to be used. This coupling 1 is also internally threaded as at 1^b for the reception of the upper end of the packer body 2.

50 Surrounding the packer body 2 and in contact with the coupling 1 is a hollow cylinder or annulus of compressible and expansible material 3, preferably of rubber, and directly below the same and in contact 55 therewith is an annular abutment 4 on which the packing 3 rests. This annular abutment 4 is preferably in the form of the frustum of a hollow cone so as to obtain a cross section of wedge form to coact with the 60 means by which the abutment 4 is anchored to the side walls of the well.

The abutment 4 and the packing 3 are 65 movable on the body 2 of the packer, but the abutment 4 is prevented from slipping down on the body of the packer by a slight

shoulder 2^a so that the contact of the annular packing 3 is always maintained with coupling 1 and with abutment 4.

On the lower end of body 2 of the packer is a collar forming a shoulder 2^b and above the same is a coupling ring 5 movable on the body member 2 by means of which an extension sleeve 6 is telescopingly connected with the lower end of the body member 2 of the packer. On the body member 2 of the packer, immediately below the abutment 4, is the means whereby the abutment 4 is anchored at will on the side wall of the well. In the present instance this is shown as a sleeve or cage 7 movable longitudinally 80 on the body member 2 of the packer together with slips 8 movably connected with the cage by means of the slip reins 8^a, the slips 8 being held normally out of engagement with the walls of the well by means of 85 springs 9, one end of each spring being rigidly connected to the cage 7 as at 7^a and the other end of said spring bearing on one of the slips above its movable connection with the cage. Aside from their function 90 of holding the slips 8 normally out of contact with the walls of the well, these springs, which are preferably semi-elliptic in form, have another important function, viz., to frictionally engage the walls and fixedly 95 support the anchor mechanism, that is to say the cage 7 and slips 8, when the body member 2 of the packer is free to move independently of the anchor mechanism, and for this purpose other and further semi-elliptic springs connected to cage 7 and 100 which do not bear on the slips 8, may be used if required or desired.

Intermediate of slip cage 7 and ring-coupling 5 is a coiled spring 10 one end of 105 which is seated on the movable coupling ring 5, the opposite end exerting an upward pressure on the cage 7.

6 indicates an extension member telescopically connected with the body member 2 of 110 the packer by means of the loose ring coupling 5, and said extension 6 is internally threaded at its lower end for reception of the coupling 11, whereby there may be suspended from the body part 2 of the packer such an additional length of tubing *a* as will, taken in connection with extension member 6, reach nearly to the bottom of the well when the packer has been lowered in the well to the lowest position it is to 115 occupy initially.

Before introducing the packer into the well, and to facilitate the lowering thereof in the well, the anchor, that is to say, the cage 7 and slips 8, should be drawn or forced 125 down on body 2 of the packer to the position indicated in Figs. 1 and 2 of the drawing, and this will compress and energize coiled spring 10 whose reaction, if not prevented, will lift the slips 8 into operative 130

engagement with the annular abutment 4. To prevent this while lowering the packer in the well, the cage 7 and slips 8 are locked down by any suitable means; in the present 5 instance the device shown is a frangible disk 12 having radially projecting lugs 12^a which extend through slots 13 in the body member 2 and take over the lower portion of slip cage 7.

10 The construction of the packer being substantially such as hereinbefore pointed out, and the cage 7 and slips 8 having been locked down in their lower position, as shown in Fig. 1 of the drawing, the tubing *a* with the 15 packer attached is lowered into the well until opposite the point where the packer is to be applied. Usually this will be near the bottom of the well, in which case the lowering of the packing may be continued 20 until the lower end of extension member *a'* touches the bottom of the well, after which the tubing will be lifted until the lower end of the extension *a'* is the required distance above the bottom of the well and the 25 extension *a'* hangs suspended from body portion 2 of the packer.

The packer being thus brought to the desired point in the well where it is to be applied, the anchor mechanism will be held 30 temporarily at such point by the frictional engagement of springs 9 with the walls of the well. A weight is now dropped into tubing *a* and in its descent it will fracture the disk 12 and release cage 7, whereupon 35 the reaction of coiled spring 10 will force the cage 7 up and bring the slips 8 into operative engagement with abutment 4 and with the walls of the well. The weight of the tubing being permitted to rest on the 40 annular packing 3, which in turn rests on abutment 4, will force the abutment down back of slips 8 and securely anchor the abutment on the walls of the well, and will also compress the annular packing 3 expanding 45 it laterally, effectively closing the space between the tubing and the walls of the well, thus shutting off all water, gas or fluid.

It is to be noted that when thus initially 50 placed in the well, the position of the packer is such that the extension *a'* is suspended from the body portion 2 of the packer, and the lower end of tubing *a'* is somewhat above the bottom of the well. If now the anchor mechanism (cage 7, slips 8) fails 55 to hold by reason of the spalling or crumbling of the walls of the well, or from any other cause, a short drop of the tubing brings the lower end of suspended extension *a'* in contact with the bottom of the well, 60 whereupon the telescoping of body member 2 of the packer into sleeve extension 6 will cause the compression of coiled spring 10, thus retarding and cushioning the descent of the tubing, and as soon as the coil of the 65 spring is closed the descent of cage 7 and

slips 8 will be arrested and the continued downward movement of body member 2 will force the abutment 4 back of slips 8 and automatically reset the packer. The cushioning of the tubing *a* in its descent and the 70 automatic and immediate resetting of the packer will effectually guard the tubing against buckling or fracture.

If now it is desired to raise the packer and reset it, without pulling the tubing, the tubing is first raised sufficiently to withdraw the abutment 4 from back of the slips 8 whereupon the reaction of semi-elliptic springs 9 will tend to force the slips 8 inward toward body member 2 of the packer 75 and out of engagement with the walls of the well, and at the same time the resistance to the upward movement of the cage 7 caused by the frictional engagement of the semi-elliptic springs 9 with the walls of the well 80 will tend to keep the coiled spring in compression, so that when the annular packing has been raised the desired distance in the well and the movement of the tubing *a* and body member 2 is reversed the expansion of 85 coiled spring coating with the semi-elliptic springs 9 will hold the cage 7 and slips 8 fixed in their new position in the well until the descent of the tubing *a* and body member 2 of the packer again forces the abutment 90 95 4 back of slips 8 and anchors the packer firmly in its new position, whereupon the annular packing 3 becomes compressed and expanded laterally and the well is effectively packed at the point selected 100 above the point where the well walls have theretofore crumbled and released the packing.

It will be noted that the walls of the well can thus be tested progressively upward 105 from the point of crumbling and the packer reset wherever the walls are found to be normal or of a character to support the packer.

Having thus described my invention, 110 what I claim and desire to secure by Letters Patent is:

1. In a well packer, the combination of a body member, an extension member suspended from and telescopingly connected with the 115 body member, an annular packing, an annular abutment for the packing, anchor devices for supporting the abutment from the walls of a well, and a spring interposed between the anchor devices and the telescoping extension member.

2. In a well packer, the combination of a body member, an extension member suspended from and telescopingly connected with the body member, an annular packing, an annular abutment for the packing, anchor devices for supporting the abutment from the walls of a well, semi-elliptic springs 125 connected with the anchor devices for frictionally engaging the walls of a well, and a 130

coiled spring interposed between the anchor devices and the telescoping extension member.

3. In a well packer, the combination of a body member, an extension member telescopingly connected with the body member, an annular packing, an annular abutment for the packing, an anchor for supporting the abutment from the walls of the well,

and a coiled spring on the body member, to said spring interposed between the telescoping extension member and the packing.

In testimony whereof I affix my signature, in the presence of two subscribing witnesses,

PATRICK H. MACK.
